UNITED STATES PATENT OFFICE

HAL F. FRUTH, OF RIVERSIDE, ILLINOIS, ASSIGNOR TO WESTERN ELECTRIC COMPANY,
INCORPORATED, OF NEW YORK, N. Y., A CORPORATION OF NEW YORK

SOUND GENERATING AND SOUND RESPONSIVE DEVICE

Application filed April 25, 1930. Serial No. 447,202.

This invention relates to sound generating and sound responsive devices, and more particularly to receivers, transmitters and microphones of acoustic apparatus wherein a 5 vibrating member is used in the reproduction, recording, analyzing and measuring of sound waves and enforced vibrations.

An object of the invention is to provide an apparatus wherein the vibratory member 10 may be damped in such a manner as to insure a uniformly accurate and faithful reproduction of the impressed vibration over a wide range of frequencies.

In order to accomplish this and other objects, the vibratory member is provided with a mounting composed of a plurality of thin laminae each of which is deformed from a true plane into an irregular or crinkly surface, so that adjacent laminae contact with each other 15 only at spaced points with the result that a yielding air cushion is provided. The irregular shape of the laminae is produced by distortional forces generated in the material itself during its manufacture, so that the laminae 20 do not tend when in use to return to a plane shape, but retain their form and resiliency indefinitely. The material of the laminae is also especially resistant to moisture and heat, with the result that the apparatus functions efficiently even under conditions of high 25 temperature and humidity.

The invention will be more fully understood from the following description taken in connection with the appended drawings in 30 which

Fig. 1 is a sectional view of a telephone transmitter embodying the invention.

Fig. 2 is an enlarged sectional view of a 35 portion of the diaphragm mounting, and

Fig. 3 is a fragmentary perspective view of a plurality of laminae in superposed position.

The transmitter shown in the drawings 40 comprises a diaphragm 10 of a common type, designed to be vibrated by the sound waves entering the transmitter, which vibrations

alternately compress and allow to expand a quantity of granular carbon or other microphonic material 12 contained in a button 14. The diaphragm bears against an annular electrode 16 surrounding its central portion, a 50 plurality of annular leaves or laminae 18 formed in accordance with this invention being interposed between the diaphragm and the electrode. At its periphery, the diaphragm is formed with a flanged portion 20 55 which extends into a recess formed by annular members 22 and 24, and a plurality of annular laminae 26, 28 formed in accordance with this invention are interposed between portion 20 and the members 22 and 24. In 60 order to facilitate assembly and retain the laminae in fixed position relative to each other perforations 30, 32 are punched through them so as to cause them to interlock.

The laminae 18, 26 and 28 are preferably 65 formed by impregnating paper sheets of about .0004" thickness with a phenolic condensation product dissolved in ethyl acetate or other suitable solvent, and drying and curing the impregnated sheets without exerting 70 pressure thereon. A suitable method of producing such sheets is to pass a film of paper through an impregnating bath, then remove the excess impregnating material, and thence pass the film over a roller, subjecting it to 75 heat while it is passing to said roller to evaporate the solvent from the impregnating material. The film may then be passed from said roller over a second roller, being subjected to a higher degree of heat to cure it 80 while passing from one roller to the other. The longitudinal tension on the film during 85 the drying and curing operations is sufficient to draw it through the impregnating bath and over the rollers, but does not prevent the paper from being deformed due to the internal stresses set up within the material of the film by the drying and curing operations, and there is no lateral tension on the paper and no transverse pressure, so that the paper may 90

and does assume a wavy or crinkly form which admirably adapts it to the purpose in view. Since the impregnated paper is baked while in such crinkly form, it does not tend, 5 under stress or age, to assume a plane shape. The laminæ formed in accordance with this invention are also especially resistant to heat and moisture, and retain their resilience indefinitely even under adverse temperature 10 and humidity conditions.

The film of paper is then punched into circular rings or laminæ 18, 26 and 28, a suitable number of such rings being superposed and held in fixed relation by means of the perforations 30, 32, preferably formed at the same time that the laminæ are punched. The rings 26 and 28 are then placed in the transmitter so as to loosely fill the space between the members 22 and 24, where their crinkly shape 20 causes them to separate, forming air pockets 34. The laminae thus form air cushions which act under the vibrations of the diaphragm to damp the vibrations thereof, the degree of damping being a function of the 25 resiliency of the laminæ, the number and thickness of the leaves, and the space provided between the members 22 and 24.

The laminæ 18 are also assembled in the transmitter in the relation shown in Fig. 1, 30 where they function in a manner similar to that above described in connection with laminae 26 and 28.

While the invention has been specifically described in connection with a telephone 35 transmitter, it is obviously applicable to the damping of vibratory members in receivers and microphones, as well as other acoustic and vibratory devices, and the shape of the laminæ will vary according to the instrument 40 in which they are used. The invention is therefore limited only by the scope of the appended claims.

What is claimed is:

1. In telephone apparatus, a vibratory diaphragm, and a damping member for said diaphragm comprising a plurality of superposed sheets of paper impregnated with a phenolic condensation product, and having a wavy contour formed by curing the impregnated 50 paper.

2. In telephone apparatus, a vibratory member, a rigid member in spaced relation thereto, and a plurality of loosely mounted thin leaves between the vibratory member and 55 the rigid member impregnated with phenolic condensation product and provided with non-registering deformations formed by stresses generated within the leaves during the process of their manufacture.

60 3. A damping member for vibratory devices used in the transmission of sound, comprising a plurality of superposed leaves of paper impregnated with a phenolic condensation product, and deformed into a crinkly 65 contour by stresses generated within the leaves

during the curing of the impregnated paper.

4. In telephone apparatus, a vibratory diaphragm, and a damping member for said diaphragm comprising a plurality of superposed leaves of phenol resin impregnated material deformed into a crinkly contour by distortional stresses generated in the material of the leaves during the process of manufacture. 70

In witness whereof, I hereunto subscribe 75 my name this 19th day of April, A. D. 1930.

HAL F. FRUTH.
